United States Patent Office.

NATHANIEL S. UNDERKUFFLER, OF NORRITONVILLE, PENNSYLVANIA.

Letters Patent No. 82,458, dated September 22, 1868.

IMPROVED SAUSAGE-STUFFER AND LARD-PRESS.

The Schedule referred to in these Letters Patent and making part of the same.

TO ALL WHOM IT MAY CONCERN:

Be it known that I, NATHANIEL S. UNDERKUFFLER, of Norritonville, in the county of Montgomery, and in the State of Pennsylvania, have invented certain new and useful Improvements in Combined Sausage-Stuffer and Lard-Press; and do hereby declare that the following is a full, clear, and exact description thereof, reference being had to the accompanying drawings, and to the letters of reference marked thereon.

The nature of my invention consists in the general arrangement of a combined sausage-stuffer and lard-press, but more particularly in the working of the follower, and in the mode of securing the different vessels to the table.

In order to enable others skilled in the art to which my invention appertains to make and use the same, I will now proceed to describe its construction and operation, referring to the annexed drawings, which form a part of this specification, and in which—

Figure 1 is a front view of the whole machine.

Figure 2, a side view of the sausage-reservoir.

Figure 3, a plan view of a part of the table; and

Figure 4 is a view of the lower end of the lever-standard.

A represents a table or bench, made of suitable size and material, resting on legs B B. One end of this table is provided with a slot, in which the lower end of the standard, C, is inserted.

This standard is cut with a shoulder and tenon, D, on its lower end, one side of said tenon being cut with a square notch, a, of the same length as the thickness of the table.

A slot, b, is also cut through the said tenon, at a suitable distance from the shoulder, so that the upper end of said slot will not come below the table when the standard is inserted.

The standard C is placed in the slot mentioned on the table A, the shoulder resting on the same. It is then moved to one side, so that the table enters into the notch a of the tenon D. A wedge, c, is then driven into the slot b, and another wedge, d, in the slot on the table, which two wedges securely fasten the standard to the table, so that it cannot come loose by working the lever.

The lever E is pivoted in the upper end of the standard C, and extends the length of the table A, or as far as may be desirable.

At a suitable distance from the standard C, on the lower or under side of the lever E, is a semicircular projection, e, which fits in the slotted upper end of an arm, F, to the lower end of which a follower is secured.

A bolt, i, passes through the said slotted end of the arm F, and through the circular projection, e, thus pivoting the arm to the lever, and this end of said arm is rounded, corresponding with a circular groove or notch in the lever E, on each side of the projection e. It will be seen, by this arrangement, that, when the follower on the lower end of the arm F is pressed downward by the lever E, the pressure is not upon the bolt i, but directly on the arm F.

The upper side of the table A is, directly under the arm F, provided with a dove-tailed recess, as shown in fig. 3, in which recess a block, G, is made to fit. On this block is firmly secured the sausage-reservoir, H, so that it will stand firmly while being used, but can easily be removed by slipping the block G out of its recess, the sides of said block being of course bevelled in a manner to correspond with the dove-tailed sides of said recess.

The sausage-reservoir H is a vessel made of any suitable material, of such size that the follower will pass freely, but at the same time snugly, up and down in the same, and on its side, near the bottom, is a tube, I, leading outward and downward, as shown in fig. 2, through which the sausage-meat is pressed by the action of the lever E on the arm F and its follower.

The vessel to press lard in consists of one outside and one inside vessel.

The outside vessel, J, has an opening on one side, near its bottom, which opening is covered with a perforated plate on the inside, and provided on the outside with a spout, K, as seen in fig. 1.

A flange extends all around the bottom of said vessel, which also fits in the dove-tailed recess on the table A, so that, when the block G is removed, it can be inserted and held firmly while it is used.

The inner vessel, L, is nothing more than a perforated cylinder, of suitable size to leave a space between it and the outer vessel, when placed in the same, and to let the follower act properly inside of the same.

The upper edge of the outer vessel is bent inward, and the upper edge of the inner is provided with a flange inclining outwards, which rests on the former, holding the inner vessel in proper position.

Having thus fully described my invention, what I claim as new, and desire to secure by Letters Patent, is—

The combination of the vessels H and J, constructed as specified, and connected, within the dove-tailed recess in the table, with the standard C, lever E, and follower F, all as herein shown and specified.

In testimony that I claim the foregoing, I have hereunto set my hand, this 23d day of July, 1868.

NATHANIEL S. UNDERKUFFLER.
